(57) **CLAIM**

The ornamental design for a battery pack power transfer adaptor, as shown and described.

DESCRIPTION

FIG. 1 is a front elevation view of a battery pack power transfer adaptor, showing my new design.

FIG. 2 is a right, side elevation view of the battery pack power transfer adaptor of FIG. 1.

FIG. 3 is a rear elevation view of the battery pack power transfer adaptor of FIG. 1.

FIG. 4 is a left, side elevation view of the battery pack power transfer adaptor of FIG. 1.

FIG. 5 is a top plan view of the battery pack power transfer adaptor of FIG. 1.

FIG. 6 is a bottom plan view of the battery pack power transfer adaptor of FIG. 1.

FIG. 7 is a front, top, right-side isometric view of the battery pack power transfer adaptor of FIG. 1.

FIG. 8 is a rear, top, right-side isometric view of the battery pack power transfer adaptor of FIG. 1.

FIG. 9 is a rear, top, left-side isometric view of the battery pack power transfer adaptor of FIG. 1.

FIG. 10 is a front, top, left-side isometric view of the battery pack power transfer adaptor of FIG. 1.

FIG. 11 is a front, bottom, right-side isometric view of the battery pack power transfer adaptor of FIG. 1.

FIG. 12 is a rear, bottom, right-side isometric view of the battery pack power transfer adaptor of FIG. 1.

FIG. 13 is a rear, bottom, left-side isometric view of the battery pack power transfer adaptor of FIG. 1; and,

FIG. 14 is a front, bottom, right-side isometric view of the battery pack power transfer adaptor of FIG. 1.

The broken lines present in the figures are included for the purpose of illustrating portions of the article that form no part of the claimed design.
